UNITED STATES PATENT OFFICE.

GEORGE M. WHITIN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

HEILMANN-TYPE COMBER.

1,273,299.

Specification of Letters Patent. Patented July 23, 1918.

Application filed February 14, 1914. Serial No. 818,616.

To all whom it may concern:

Be it known that I, GEORGE M. WHITIN, a citizen of the United States, residing at Whitinsville, in the county of Worcester and State of Massachusetts, have invented the following described new and useful Improvements in Heilmann-Type Combers.

The object of the invention is to improve the combing efficiency of cotton combers of the Heilmann type and more especially to prevent loss of good fiber in the form of waste. To this end the invention consists of a new comb motion by which the top comb is depressed to its full extent at a point in advance of the tails of the first fibers passing thereunder, and from a point sufficiently elevated at the moment when the detaching roll is receiving the head end of the fringe or tuft, as not to impede the free passage of the fringe thereunder. The new motion thus permits the tufts to be more securely nipped by the detaching roll before the top comb teeth settle therein and insures that the tuft receives the full combing action of the top comb, thereby producing a marked improvement in the quality of the sliver and materially reducing the percentage of waste. The invention also consists in a new relation of the lap-feed mechanism to the other parts of the machine and particularly to the top comb motion first referred to, all as will be hereinafter fully explained and more particularly pointed out in the claims.

In illustration of the invention reference may be had to any common type of Heilmann comber, such as represented in the accompanying drawings, in which Figures 1, 2 and 3 represent vertical transverse sections of the detaching elements of the comber with the parts in several successive positions.

Fig. 6, a graphic representation of the path of the top comb with relation to the segment;

Fig. 5, a view of the top comb controlling means;

Fig. 4, a top plan of a comber frame including the invention but omitting numerous parts of the well-known structure not directly pertinent to the invention; and

Fig. 7 is a diagrammatic view in section indicating the relation of the feed mechanism drive to the other parts.

The comb cylinder shaft 1 may be com-

mon to all of the combing heads of the machine, as shown in Fig. 4, carrying a comb cylinder for each head, each of which cylinders comprises a needle half-lap 2 and a detaching half-lap or segment 3, the former for combing the forward or head end of the fringe of lap that is held by the nippers and the latter for detaching such fringe in the form of a tuft. The nippers comprise a lower jaw or cushion-plate 4 so called, and an oscillating movable jaw or nipper knife 5. The cushion plate may be mounted on the machine frame to be operative in about the position indicated, and the nipper knife may be carried by the arms 6, of any suitable form and mode of operation. The feed rolls 7 and 8 behind the nippers are held under nipping pressure by the spring-pressed feed-roll arms 9, and are operated at the appropriate time to advance the end 60 of the lap through the open nippers. The lower feed roll 7 is formed on a shaft extending the length of the machine, as usual, and is driven by a gear 24 at its end which gear is driven by a pinion 25, the latter being connected to a star-wheel 26 to be operated once on every revolution of the comb cylinder shaft, 1, by a stud wheel 27 carried on the latter. Fig. 7 represents the relation 65 of this gearing, but for convenience of illustration omits the journals and supporting brackets which may be assumed to be of any suitable character. The drawing does not attempt to give an accurate representation 70 of the gear ratios of the mechanism, and it 75 will be understood that they be such as to feed the lap forwardly a desired distance on each operation, that is to say about a quarter or three-eighths of an inch under ordinary circumstances. The feed rolls might 80 be driven by other agencies than above described, as will later appear, and in any event are so arranged as to afford a short path from their bite-line, on which they 85 hold the lap, to the bite-line of the detaching roll on the segment. For this purpose the top feed roll 8 is of relatively small diameter and held by its holder arms 9 on the forward side of the lower roll, as described and shown in a co-pending application, filed June 13, 1913. 90

When the nipper knife closes on the end of the lap, it holds it projected into the path of the needle half-lap 2, which combs it in the usual manner, after which operation the 95 100 105 110

segment next engages the combed fringe and presses or grips it against the under side of the detaching roll 10, with which the segment co-operates to detach the tuft from the body of the lap. The needles of the half-lap 5 will have acted on the fringe up to the point marked *a* Fig. 1, all of the lap behind that point having been held by the nippers during the cylinder combing. The detaching 10 roll is assumed to be a leather-covered roll, in the present case, and to be rotated by its frictional engagement with the segment, but that might be otherwise so far as this invention is concerned. As shown herein 15 also, the segment is radially higher on the cylinder shaft than the points of the needle half-lap so that the detaching roll 10 may thus normally occupy a position on fixed end seats, on which seats it will escape the 20 needles and be engaged by the segment; but this also might be otherwise, so long as the roll and segment are brought into engagement at the proper time. When such engagement takes place the head end of the 25 partly combed tuft is gripped thereby and drawn away from the main body of the lap, held by the feed rolls, the nippers being then open, or opening, and is passed forward to the means by which such tufts are overlapped or pieced with other previously 30 detached tufts. The piecing may take place according to the usual or any suitable manner and the means for doing it are therefore not shown herein. They may, for example, 35 consist of an intermittently or alternately rotated piecing roll engaging the detaching roll, such as shown in Rooney Patent No. 822,479, or of a separate system of rolls, such as shown, for example, in the co-pending 40 application filed June 13, 1913. While the tuft is being thus drawn forward by the coaction of the detaching roll and segment, the tail ends of its component fibers are combed by the top comb 11. This comb may, 45 itself, be of ordinary, single or double, construction mounted, with the usual provision for angular adjustment, at the ends of the top comb arms 12, which latter are hinged to the top comb shaft 13 in such manner that 50 the comb can be lifted or turned back manually when desired, swinging on the shaft, but by rocking the shaft can be lifted automatically on each nip of the comb. For this purpose the shaft carries a sleeve lug 55 14, with a thrust screw 15 therein, adapted to abut against an opposing short arm 16 extended downwardly from the hub of the top comb arm 12, this being a usual form of connection between the top comb shaft and 60 the top comb, in all combers where the combs are mechanically lifted. It will be understood from Fig. 4 that the shaft 13 extends through all the heads of the machine, and that all the top comb arms of the machine 65 are mounted thereon in a similar manner.

In order that the combing by the top comb may be complete and thorough, it should penetrate the tuft at a point in advance of the point *a* above referred to, and for the best effect it should also be well settled in 70 the tuft at or before that point, since the combing efficiency of the top comb is directly proportional to the depth to which its teeth enter the tuft. The present invention brings the comb promptly to its full penetration in 75 the tuft.

In those prior art combers which have oscillating top combs, the latter approach the tufts with a gradual movement, and in order to reach the point of lowest depression 80 immediately after the detaching roll has taken hold of the fibers (or so as to engage the tufts in advance of the point *a*) they must start their depressing movement well in advance of the beginning of the detaching period, in which case, however, and because of the gradual character of the descent and relative high speed of the tuft, they will be so low when the head of the fringe is 85 approaching and entering under the detaching roll as to encounter and obstruct many of the best fibers, making waste of them; and if the timing of the top comb is retarded so as to be in a non-obstructive position at the 90 moment of said approach and entrance, then it will not reach its lowest and most effective position until after the foremost fibers composing the tuft have passed beyond it, and a comb so controlled can in no event become fully depressed in advance of the point *a*, 95 without blocking a great many of the fibers and making waste of them. The same is true of the stationary top comb. To eliminate this waste and at the same time gain the benefit of thorough top-comb combing, I control the 100 depressing motion so that while the comb may start to descend (if desired) before the tuft enters under the roll, or at any desired point according to the setting, it nevertheless does not reach an obstructive or 105 waste-making position until the roll has gripped the tuft and then, being very close, and almost in combing relation, to the tuft, it suddenly descends the rest of the way 110 quickly reaching its lowest and most effective point. Since the foremost fibers are all gripped and held by the detaching roll, at that instant, only the leaf and very short fibers will be retained by the top comb. 115

Figs. 1, 2 and 3 represent three successive 120 positions of the descending top comb controlled in the manner first referred to. In Fig. 1 the detaching roll is just about to nip the head of the advancing tuft against the segment; the top comb is well above it and 125 not obstructing the entry of the fiber heads thereunder. In Fig. 2 the head of the tuft is firmly gripped by the detaching roll, and the top comb has descended slowly and very slightly,—a preparatory movement,—to the 130

point where it is ready for its quick descent. In Fig. 3 it has dropped its full extent well within the length of the first fibers of the tuft (which cannot be readily illustrated in this figure), and also somewhat in advance of the point α above referred to. The final descent is so rapid that it takes place before the segment and detaching roll have advanced the first fibers from below the top comb. In Fig. 6, for convenience of observation, the path of motion of the depressing top comb is graphically diagrammed, assuming the segment and the tuft upon it to be stationary and that the top comb has angular movement about the center 1, in addition to its controlled descent. If radius b in this diagram represents the point where the head ends of the tuft are firmly gripped by the detaching roll, radius a will correspond to the point α above referred to, that is to say, to the point to which the tuft has been combed by the needle half-lap of the cylinder, as above explained, and c may represent the general position on the segment of the tail ends of the foremost fibers. The top comb starting from a point f in advance of the radius b and well elevated above the segment, which point may represent its highest elevation, descends slowly toward the point of intersection (g) with the dotted circle d . This circle represents a permissible degree of elevation of top comb above the segment which will not obstruct the passing of the tuft under it to the extent of wasting good fibers, such as the top comb ordinarily throws down when in its operating position during the gripping of the tuft by the detaching roll; its position can be readily determined in any comb. For convenience of reference and also for lack of a better term, the degree of elevation represented by this circle will be referred to herein and in the claims as the waste limit, since it represents an elevation at which the comb will no longer be encountered by the upturned forward ends of the tuft fibers passing beneath it so as to turn back such fibers making waste thereof as above explained. It will be seen that the path of the top comb, represented by the heavy line, intersects the radius b well above this waste limit circle, indicating that the said comb is therefore non-obstructive to the fibers at the moment of detaching-roll-gripping. From its point of intersection with the circle d , the path inclines abruptly downward to the dotted circle e , representing the sudden descent of the teeth. This circle represents the lowest working depression of the top comb, and is generally elevated above the surface of the segment a distance which will be just sufficient to prevent contact therewith; the lower it can be, the better will be the combing. The path meets the circle in the case illustrated in

Fig. 6, somewhat in advance of both radii c and a , that is to say before the passing of the still uncombed portion of the tuft lying between α and c . The abrupt part of the top comb path should be as steep as possible and should in any event take place between the radii b and c , and preferably between the radii b and a , so that the whole of each of the foremost fibers of the tuft will be thoroughly combed by the top comb in its lowest position.

In attaining such abrupt depression of the oscillating top comb, I may use various mechanical means but prefer a simple cam such as indicated in Fig. 5, arranged to operate the arm 17 of the comb shaft 13. The latter shaft is journaled in the rear portions of the frame uprights 23 between the combing heads, as usual, and at the delivery end of the machine carries a weighted arm 17', serving as a counter-balance tending to minimize the effect of torsion in the shaft. The free end of the cam arm 17 is provided with a wear-piece by which it rests on the edge of the hardened steel cam 18, and the latter is mounted on a shaft, such as 19, which is to be understood as rotating in phase with the comb cylinders. The gearing for this purpose is indicated only in a general way in Fig. 4, but the cam could be mounted on the comb cylinder shaft, 1, or elsewhere as desired and according to the character of the drive head. It is only necessary that it operate the top combs once for each nip of the machine. Its contour provides an easy or gradual lifting of the arm 17 and the top combs, which may begin from a point such as s and continue to a point such as f' , and is followed by a gradual decline to the point g' where the arm rides off the end of the cam, giving the abrupt depression already indicated at f , g , in Fig. 6. The cam is set on its shaft so that the edge g' passes the nose of the arm 17 at a point corresponding to g in the diagram, so that the final and complete depression thus takes place before the fibers have passed beneath the comb as already explained. The abrupt drop of the cam need be only sufficient to bring the points of the top comb teeth from the waste limit or slightly above it, to the deepest penetration (circle e), and when the arm rests on the low part of the cam, it is desirable that all the stop screws 20 of the top comb arms 12, shall also be simultaneously resting on their fixed abutments 21, so that lost motion and torsion in the shaft 13, as well as tendency to rebound will be avoided so far as possible. In order to hasten the action of the arm 17, a strong spring 22 is applied thereto, acting in the obvious manner.

While other forms of quick depression mechanism might obviously be employed, I prefer a cam such as just described, which raises the combs slowly and drops them ab-

ruptly, and more particularly a cam which begins to lower the combs toward the waste limit in advance of the abrupt descent, as provided by the gradual decline f^1, g^1 , but the invention is not limited to this preferred form, except as pointed out in the claims. The gradual raising of the top comb, and which occupies the greater part of the cycle of one nip, serves also to distribute the load 10 on the cam and hence on the machine as a whole. It will be noted that the top comb rises and falls always in the same path.

The top comb axis, or operating shaft 13, may occupy its usual position and is desirably located sufficiently low with respect to the feed and detaching rolls to prevent retrograde movement of the needles with respect to the tuft, that is to say, so that the needles will swing directly into the tuft and 15 forwardly rather than rearwardly during the act of penetration therein, and it will be evident that such shaft or axis can be disposed lower down than indicated in Fig. 1. The detaching roll 10, it will also be evident, should be as slender as consistent with the width of the lap served by the comber, in order that the top comb may enter the tuft as near as possible to the bite line upon the segment.

30 The time relation of the lap feed mechanism to the other parts is indicated by Fig. 7, wherein it will be seen that the stud 27 enters and starts the rotation of the star-wheel 26 immediately after detachment, that 35 is to say, the lap is advanced immediately following the separation of the tuft from the body of the lap and not prior to or during the detachment as heretofore. Such timing of the feed results in a longer fringe 40 left projecting from the closed nippers to be combed by the cylinder needles 2, thereby benefiting the appearance of the resulting sliver because of the better polishing given to the fibers. In the present case such timing also directly coacts with the new top 45 comb motion, since the point α is thus held back, as it were, until after the top comb has completed its abrupt descent, thus insuring the most efficient combing action. Otherwise the feed rolls might advance the tuft 50 too far for the top comb to reach its point of deepest penetration (circle e) in advance of the point (or radius) α which would sacrifice thoroughness of combing by so much. However, the new top comb motion may be and is used with such early timing of the feed, since thereby a slightly less percentage of waste is made than when the feed takes place after detachment; and in 55 any event, the angular position of the stud 27 on the shaft 1, is made adjustable, so that the feed may be set to take place at either time, that is to say, either previously to detachment, subsequently thereto or coincidently therewith, according as it may be de-

sired to produce the very lowest percentage of waste or the very best quality of combing. The control of the top comb above described serves in either case to improve the efficiency of the comber as a whole and as will be evident from the explanation above made. 70

I claim:

1. In a Heilmann cotton comber, the combination with the lap feed mechanism, the comb cylinder, the detaching segment thereon and a detaching roll engaged by the segment, of an actuated top comb and controlling means therefor producing a gradual rise and relatively abrupt descent of said comb in the same path, such descent taking 80 place during the engagement of said roll with the tuft.

2. In a Heilmann cotton comber, the combination of the comb cylinder having a detaching segment and a detaching roll engaged thereby, of an oscillated top comb and means for controlling the same, comprising a cam, formed to gradually raise and permit abrupt depression of the top comb in the same path. 85

3. In a Heilmann cotton comber, the combination of the comb cylinder having a detaching segment, a detaching roll engaging the latter, and an oscillated top comb, controlled to move from its waste limit—*i. e.*, 95 the position of approach to the tuft in which it begins to throw down waste,—to its lowest depression during the interval between the gripping of the tuft on the segment and the passage of the first fibers thereunder. 100

4. In a Heilmann cotton comber, the combination with a cylinder having a needle-half-lap and a detaching segment, means for holding the lap in contact with the needle-half-lap, and a detaching roll engaging the segment, of an actuated top comb controlled to move from its waste limit—*i. e.*, 105 the position of approach to the tuft in which it begins to throw down waste,—to its lowest depression during the interval between the gripping of the head of the tuft and the passing of the cylinder-combed portion thereof beneath the top comb. 110

5. In a Heilmann cotton comber, the combination with the lap feed mechanism, the comb cylinder having a detaching segment and a detaching roll to engage it, of a depressing top comb and means for moving the same from an elevation above its waste limit,—*i. e.*, the position of approach to 115 the tuft in which it begins to throw down waste,—through such limit to its lowest depression during the interval between the gripping of the head of the tuft upon the segment and the passing of the foremost fibers from beneath the top comb. 125

6. In a Heilmann cotton comber, means for nipping and feeding the lap, a comb cylinder provided with a needle half-lap and a detaching segment, a detaching roll 130

engaging the latter to detach the tuft, means for starting the feeding means after such detachment and a top comb engaged with the said tuft prior to the detachment.

- 5 7. In a Heilmann cotton comber, the combination of the lap nipping and feeding means, the comb cylinder having a detaching segment, a detaching roll coating therewith to detach a tuft from the lap, 10 means for starting the feeding means immediately after tuft-detachment, a depressing top comb and means for causing the same to move from its waste limit—*i. e.*, the position of approach to the tuft in which 15 it begins to throw down waste,—to its lowest depression in the interval during the passage of the foremost fibers of the tuft beneath it.

8. In a Heilmann cotton comber, the combination with the lap feeding and nipping means, the comb cylinder having a detaching segment, a detaching roll to engage the latter, and an oscillated top comb rising and falling in the same path, of controlling 25 means for the latter comprising a top comb shaft, an arm connected to the latter, and a rotary cam engaging the arm, the contour of such cam including an edge adapted to ride under the arm and permit a quick 30 depression of the top comb.

9. In a Heilmann cotton comber, the combination of a series of combing heads comprising means for feeding and combing the laps and detaching the tufts and including 35 a top comb for each head, an actuating shaft for the top combs, means for operating the shaft, to give a quick depression of the top combs directly following the tuft-engagement, and means applied to said shaft to 40 reduce the torsional displacement therein on such depression.

10. In a Heilmann type cotton comber, the combination of a series of combing heads comprising detaching rolls and top 45 combs, an actuating shaft for the top combs, means for operating the shaft to give a quick depression of the top combs and a counter weight on the shaft.

11. In a Heilmann type cotton comber, 50 the combination with the lap feeding and nipping means, a comb cylinder having a detaching segment and a detaching roll therefor, of a top comb and controlling means therefor, comprising a spring and a 55 cam device whereby the top comb is subject to quick depression during the for-

ward passage of the tuft upon the segment.

12. In a Heilmann type cotton comber, the combination of a top comb shaft having a series of top combs actuated thereby, 60 detaching segments and detaching rolls for the latter, and controlling means whereby the top combs are depressed from the waste limit—*i. e.*, the position of approach to the 65 tuft in which it begins to throw down waste,—to the point of lowest depression during the passing of the forward fibers of the tuft thereunder.

13. In a Heilmann type cotton comber, 70 the combination with feed rolls and nipper jaws, a comb cylinder having a half-lap and a detaching segment, and a detaching roll 75 engaging the latter, of a top comb adapted to oscillate between the nippers and detaching roll and controlling means therefor comprising a spring and means for sustaining the top comb at or above its waste limit—*i. e.*, the position of approach to the tuft in which it begins to throw down 80 waste,—and dropping the same under the action of said spring, during the passage of the tuft beneath the top comb.

14. In a Heilmann type cotton comber, the combination of an actuated feed roll, 85 means for nipping the end of the lap, a comb cylinder for combing the same, a detaching roll adapted to detach the tuft from the lap, and means for starting such actuated feed roll in motion to advance the lap 90 immediately following the tuft detachment.

15. In a Heilmann type cotton comber, a series of combing heads, a top comb shaft having a top comb, a detaching segment and a detaching roll for each head, and controlling means whereby the top comb is depressed from its waste limit to its lowest depression after the head of the tuft has been gripped by the detaching roll, in combination with a feed roll adapted to hold 95 the lap stationary while the tuft is being gripped, and means for rotating such roll to advance the lap immediately following 100 detachment of the tuft.

In testimony whereof, I have signed this 105 specification in the presence of two witnesses.

GEORGE M. WHITIN.
